CONTROL PANEL FOR A WASHING MACHINE OR SIMILAR ARTICLE

Montgomery Ferar, Huntington Woods, Mich., assignor
to Whirlpool Corporation, St. Joseph, Mich., a corpora-
tion of Delaware

Application July 16, 1957, Serial No. 46,963

Term of patent 14 years

(Cl. D49—1)

FIG. 1

FIG. 2

FIG. 3

Figure 1 is a front perspective view of a control panel for a washing machine or similar article embodying my new design;

Figure 2 is a cross-sectional view taken on the line 2—2 of Figure 1; and

Figure 3 is a side elevational view of the control panel of Figure 1, further illustrating my new design.

I claim:

The ornamental design for a control panel for a washing machine or similar article, as shown.
